[57] **CLAIM**

The ornamental design for a display shelf, as shown.

DESCRIPTION

FIG. 1 is a front perspective view of a display shelf showing my new design;

FIG. 2 is an inverted rear perspective view showing the bottom and side not seen in FIG. 1, with the opposite side being omitted for convenience of illustration;

FIG. 3 is a rear elevational view in an upright position;

FIG. 4 is a front elevational view thereof;

FIG. 5 is a side elevational view thereof; and

FIG. 6 is a bottom plan view thereof.

Fig. 3.

Fig. 4.

Fig. 6.
